UNITED STATES PATENT OFFICE.

HENRY CALVIN WINEBRENNER, OF BALTIMORE, MARYLAND, ASSIGNOR TO
THE SCOTT MANUFACTURING COMPANY OF BALTIMORE CITY.

STEAM-CRANE.

SPECIFICATION forming part of Letters Patent No. 337,724, dated March 9, 1886.

Application filed September 25, 1885. Serial No. 178,130. (No model.)

To all whom it may concern:

Be it known that I, HENRY CALVIN WINEBRENNER, of the city of Baltimore and State of Maryland, have invented certain Improvements in Steam-Cranes, of which the following is a specification.

This invention relates to the combination, with crane, of a steam-engine with its steam and exhaust pipes situated in a line corresponding with the axis of the post, whereby the crane may be turned in any direction without affecting the admission to and exhaust of steam from the engine.

It further relates to details of construction of certain parts of the crane, as will hereinafter fully appear.

The drawing forming a part hereof is a side elevation, partly in section, of a crane embodying my improvements.

A is the post of the crane, having at its lower end the gudgeon *a*, which rests in a step, *b*. The upper end of the post is supported by means of a pipe, *c*, which passes through and is adapted to turn freely in collars *d*, secured to a frame, *B*, which may be a portion of an upper floor. The pipe *c* is connected to the post *A* by means of a collar, *e*, having legs *f* let in and bolted to the post *A*. The upper end of the pipe *c* enters a stationary chamber, *C*, through a stuffing-box, *g*, and is supported by a flange, *h*, which rests on a ring, *i*, supported by set-screws, as shown. This pipe *c* forms a part of the steam-pipe, and is attached at its lower end to a second chamber, *D*.

E represents the engine, which is of the rotary type and needs no description herein, as it forms no part of my present invention.

The steam-pipe *j*, which leads from the boiler, (not shown,) enters the chamber *C*, and a second steam-pipe, which connects directly with the engine, is denoted by *k*.

The exhaust-pipe *l* from the engine passes entirely through the chamber *D*, the pipe *c*, and the other chamber, *C*, and may extend above the chamber to any desired height.

The chambers *C* and *D* are provided with stuffing-boxes, to prevent escape of steam, and the exhaust-pipe *l*.

It will be seen that in the swinging motion of the crane the pipes which move with it maintain under all circumstances an axial position, and the flow of steam is therefore not interfered with.

I claim as my invention—

1. In combination with a crane, a steam-engine with a portion of its steam and exhaust pipes placed in a line corresponding with the axial line of the crane-post, whereby the flow of steam to and from the engine is not interfered with in the swinging of the crane, substantially as specified.

2. In combination with the swinging post of a crane, a steam-chamber situated above the post and on the axial line thereof, centrally-placed steam and exhaust pipes, and a steam-engine, substantially as specified.

3. In combination with the swinging crane-post *A*, the chambers *C* and *D*, connecting pipe *c*, steam-pipes *j* and *k*, and exhaust-pipe *l*, substantially as specified.

HENRY CALVIN WINEBRENNER.
